MACHINE FOR USE IN THE MANUFACTURE
OF SHOESLloyd G. Miller, Beverly, Mass., assignor to
United Shoe Machinery Corporation, Flemington, N. J., a corporation of New Jersey

Application March 17, 1948, Serial No. 15,304

17 Claims. (Cl. 12—1)

1

This invention relates to a machine for use in the manufacture of shoes and particularly a machine for assembling an upper on a sole member.

In the manufacture of certain types of slip-lasted shoes, a pre-cut upper, having a lasting margin of a definite and predetermined width, is loosely assembled on an insole and adhesively secured thereto with its lasting margin overlaying the insole. When the upper has thus been assembled on, and secured to, the insole, a last is inserted to stretch and shape the upper, after which an outsole and heel are attached to the bottom of the shoe, in the usual manner, to complete the shoe. The operation of assembling the upper on, and adhesively securing it to, the insole, is usually performed by hand and extreme care must be exercised to insure that the lasting margin is accurately positioned with its full width overlaying the insole, and also that the lasting margin is firmly and uniformly pressed against the insole. Frequently the insole is rabbeted to provide a locating shoulder, in which case care must be exercised to see that the edge of the upper is placed against this shoulder. At best, this hand-assembling operation is relatively slow and tedious and, unless very carefully performed, is not productive of satisfactory results.

It is, therefore, an object of this invention to provide a novel machine by the use of which this assembling operation may be easily and speedily performed with uniform and satisfactory results. To this end, the herein illustrated machine is provided with means constructed and arranged to extend into the open end of an upper for supporting a sole member, with the upper loosely assembled thereon, together with means for applying pressure to the upper and sole member, progressively, to secure the upper to the sole member in assembled relation thereon. More particularly, and in accordance with features of this invention the supporting means may comprise a table which is supported on a flexible arm and arranged to extend into the open end of an upper, while the pressing means comprises an anvil, supported, for circular movement, on a flexible arm adjacent to the table and arranged also to extend into the open end of the upper, and a rotary pressing member co-operating with the anvil for applying pressure to and feeding the overlapped lasting margin of the upper and sole member to secure the upper progressively to the sole member in assembled relation thereon.

For holding the sole member on the supporting

table, during the assembling operation, the herein illustrated machine, in accordance with another feature of the invention, is provided with a holdown member which is arranged to bear yieldingly against the sole member. Preferably, this holdown member is adapted also to serve as a guide means for positioning the edge of the lasting margin of the upper relatively to the sole member and is particularly useful when an upper is being assembled on a sole member that is not rabbeted or otherwise provided with means for locating the upper thereon.

In order that the sole member, with the upper loosely assembled thereon, may be conveniently positioned laterally on the supporting table, and relatively to the anvil and rotary pressing member, the herein illustrated machine is, in accordance with a still further feature of the invention, provided with an edge guide which is arranged to contact the upper adjacent to, and where it is bent around, the edge of the sole member. Preferably, and as herein illustrated, means are provided for withdrawing the edge guide away from its operating position closely adjacent to the anvil, and for simultaneously elevating the holdown so as to facilitate the placing of a sole member, with an upper loosely assembled thereon, upon the supporting table at the beginning of the assembling operation. Also, in order further to facilitate the introduction of the work, the means for withdrawing the edge guide and for elevating the holdown, is also adapted to bring the machine to a stop with the presser member and anvil separated.

The above and other objects and features of the invention will be apparent from the following detailed description of the machine illustrated in the accompanying drawings, and will be pointed out in the claims.

40 In the drawings:

Fig. 1 is a view in front elevation of two machines, each embodying the features of this invention;

Fig. 2 is a view in side elevation of the machine shown on the right in Fig. 1;

45 Figs. 3 and 4 are plan views, respectively, of the operating elements of the two machines shown in Fig. 1;

Figs. 5 and 6 are views in front elevation of the operating elements of the machine shown in Fig. 4, with these operating elements in different positions;

Figs. 7 and 8 are views in side elevation of the operating elements of the machine disclosed in Figs. 4, 5 and 6;

50 Fig. 9 is a view in front elevation showing the

operating elements of one of the machines in position to receive the work;

Fig. 10 is a view similar to that of Fig. 5, but showing the machine operating on a different type of work; and

Fig. 11 is a perspective view of a partially completed shoe after its upper has been assembled on an insole.

Referring now to the drawings, the two machines which are illustrated in Fig. 1 are exactly alike except that the relative positions of their operating elements are reversed, for a purpose to be explained below. Accordingly, while the following description refers particularly to the machine shown on the right in Fig. 1, and in side elevation in Fig. 2, this description also applies to the various elements of the machine shown on the left, which elements are identified by the same reference characters.

The operating elements of each of the machines comprise a rotary presser member 10, a cooperating anvil 12, a work-supporting table 14, a holdown 16 and an edge guide 17. In each machine, these operating elements are supported on, and operated by mechanism associated with, a vertical column 18 having a base flange 20. As illustrated in Fig. 1, the two machines may conveniently be supported on the same base member 22, with their operating elements facing each other, and the elements of both machines driven from a main power shaft 24.

Referring now to the machine shown on the right in Fig. 1 and in side elevation in Fig. 2, the presser member 10 is eccentrically mounted in a chuck 30 which is secured to the outer end of a shaft 32. This shaft is journaled in a bearing bore 36, formed in the upper portion of the column 18, and carries a sprocket 38. Journaled in the lower portion of the column are two shafts 40 and 42 which are connected together by means of spur gears 44 and 46, carried respectively by these two shafts, and a gear 48, journaled on a stud 50. Formed integrally with the gear 48 is a second sprocket 52 which is connected to the sprocket 38 by means of a chain 54. The shaft 42 carries a pulley 56 and is driven by means of a belt 58 which extends from the pulley 56 to a pulley 60 on the power shaft 24.

The anvil 12 is located directly below the presser 10 and has a portion 61 which extends beneath the table 14 and is secured to a curved flexible arm 62 by means of screws 63, Figs. 7 and 8. This flexible arm has a downwardly extending rigid portion 64 which is supported on two eccentric pins 66 and 68, carried by the shafts 40 and 42, respectively. The arrangement of these eccentric pins, with respect to the eccentrically mounted presser 10, is such that when the shafts 32, 40 and 42 are rotated, from the main power shaft 24 as above explained, the presser 10 is rotated and the anvil 12 moved in a circular path, so that relative approaching and separating movements are imparted to the presser 10 and the anvil 12.

The table 14 is formed integrally with a curved, flexible arm 70 which is secured to a horizontal bar 72. This bar is adjustably connected, by means of screws 71, to the upper end of a supporting bracket 73 which is fastened to the base flange 20 by means of screws 74, see Fig. 1. Directly above this table is the holdown 16 which is supported for yielding movement upwardly, against a coil spring 76, in a bracket member 78. This bracket member is carried on the outer end of a lever 80 which is fulcrumed

on a support 82 on the top of the column 18. A coil spring 84 is arranged to hold the lever 80 yieldingly in the position, shown in Figs. 1 and 2, as determined by an adjustable stop screw 86, 5 carried by an extension 88 of the support 82. The lever 80 is connected, by means of a chain 90, to one end of an L-shaped lever 92 which is pivotally mounted on the face of the column 18 by means of a screw stud 94, see Fig. 2. Connected to this same end of the lever 92 is a treadle rod 96 which extends downwardly to a treadle, not shown. When this treadle is depressed, the lever 92 is turned, against the action of a coil spring 98, in a direction to pull 15 down on the chain 90 and thus to elevate the holdown 16 to the position in which it is shown in Fig. 9.

The edge guide 17 is yieldingly supported, 20 against a spring 100, in a bracket member 102 (Fig. 1). This bracket member is adjustably secured, by means of screws 104 and a slot 106, to an arm 108 which is pivotally mounted on a pin 110 carried by a bracket 112, secured to the face of the column 18 by means of screws 114, see Fig. 25. The arm 108 has a downwardly extending portion 116, provided with a hole 118 into which a pin 120, carried by the lever 92, extends. Thus, when the treadle, not shown, is depressed to elevate the holdown 16, in the manner just explained, 30 the arm 108 will be turned on the pin 110 so as to swing the edge guide 17 away from the anvil, see Fig. 9.

In order to facilitate the introduction of the work, when the treadle is depressed and the holdown 16 and edge guide 17 moved to the positions shown in Fig. 9, as above explained, mechanism is also provided for stopping the rotation of the shafts 32, 40 and 42 with presser 10 and anvil 12 separated. This mechanism comprises a collar 130 which is secured to the shaft 40 and provided with a lug 132, see Fig. 2. Adjacent to the screw stud 94, the lever 92 is formed to provide an ear 134. When the treadle, not shown, is released, this ear is held out of the path of rotation of the lug 132 on the collar 130. However, when the treadle is depressed, the lug 132 will engage the ear 134, thus causing the belt 58 to slip and stopping the rotation of the shafts 32, 40 and 42 with the presser 10 and anvil 12 separated as shown in Fig. 9. The belt 58 is made loose enough to permit this slipping action while being capable of transmitting sufficient torque to the pulley 56, when the treadle is released and the ear 134 moved out of the path 55 of the lug 132, to provide all of the power required for operating the machine.

Referring now particularly to the machine which is shown on the right in Fig. 1 and the operating elements of which are illustrated in Figs. 4 to 8, the operation of this machine, which is, of course, similar to that of the machine shown on the left in Fig. 1 and in Fig. 3, will be explained. The operator first takes a sole member, for example the insole I, which is shown as rabbed to provide a locating shoulder S, see Figs. 3 and 4, and loosely assembles thereon an upper U which is precut with a lasting margin of suitable width. It will be understood that the rabbed portion of the insole I and the inside surface of the lasting margin of the upper U will be coated with adhesive so that these parts will adhere together upon the application of pressure.

Holding these loosely assembled parts in his hands after depressing the treadle to elevate the

holdown 16, to move the edge guide 17 away from the anvil, to separate the presser 10 and anvil 12 and to stop the machine with the parts in the positions shown in Fig. 9, the operator places the insole on the table 14 with the toe end of the upper beneath the presser 10 and above the anvil 12. Now, after lining the edge of the lasting margin of the upper U with the shoulder S on the insole I, the operator releases the treadle thus lowering the holdown against the top of the insole to hold it yieldingly against the table, moving the edge guide to the position shown in Figs. 3, 4, 5 and 6, and starting the machine. As the shafts 32, 40 and 42 rotate, the presser 10 rotates and anvil 12 travels in a circular path, in time relation, so that the presser and anvil move toward and away from each other. Because of this action, the lasting margin of the upper is pressed firmly against the marginal edge of the insole and the upper and the insole are fed along in the direction of the arrow in Fig. 7. As will be apparent, the anvil 12 and table 14 can yield downwardly, because of the flexibility of their supporting arms 62 and 70, thus accommodating insoles of different thicknesses. When the presser and anvil separate, see Fig. 8, the insole and upper are held against movement by the yielding pressure of the holdown 16.

As the upper is thus progressively secured in assembled position on the insole, by the action of the presser 10 and anvil 12, the operator guides the upper manually so that its edge is located against the shoulder S. The inside edge of the bottom of the holdown 16 serves as a guide point for assisting the operator in thus locating the edge of the upper. This holdown may also serve as a means for locating the edge of the upper when the machine is operating to assemble an upper to an insole which has no rabbeted portion. Fig. 10 shows the machine operating under these conditions and with the edge of the upper engaging the holdown. The insole is located in a widthwise direction with respect to the anvil 12 and table 14 by the engagement of the upper, as it is bent around the corner of the insole, with the edge guide 17. The operator continues this operation until the upper is completely assembled and secured to the insole along one side. The insole and the partly assembled upper are now removed from the first machine and the assembling operation repeated along the opposite side of the insole, in the other machine, see Fig. 3, so as to complete the assembling of the upper on the insole. Fig. 11 shows an upper thus completely assembled on an insole.

While the machine of this invention has been shown, for the purpose of illustration only, as used for assembling the upper of an open-toe and open-heel shoe on an insole, it will be understood that the machine is not limited to assembling uppers of this kind. For example, an upper having a closed heel may be assembled on the insole, progressively, from toe to breast line on the opposite sides of the insole. Subsequently, after the last has been inserted, the heel end of the shoe may be lasted in the usual manner. Similarly, an upper having a closed toe may be assembled on an insole, rearwardly from points adjacent to the tip line. Thereafter, when the last has been inserted, the toe end may be lasted in the usual manner. As will be apparent, similar procedures may be followed where the upper has both a closed toe and a closed heel.

Whatever the type of upper that is assembled

on, and secured to, the insole, the next step in the manufacture of the shoe is that of inserting the last to stretch and shape the upper. It is the usual practice so to cut the upper that, when its full lasting margin is secured to the insole, the last will fit the upper snugly enough to stretch it somewhat when the last is inserted. As will be apparent, this procedure requires the very careful grading of the upper, as well as accurate positioning of the lasting margin of the insole, if the desired stretching of the upper is to be obtained. Substantially the same results may, however, be obtained more easily by departing from the usual procedure in the following respects.

First, the upper is cut a little smaller than the last which is to be inserted in it. Next, the upper is secured to the insole, during the assembling operation as carried out in the machine of this invention, with a so-called "leggy" cement, such, for example, as natural or synthetic latices or cements. Now, after the upper has been assembled with its full lasting margin overlapped on the insole, when the last is inserted, it being larger, will more than fill the upper and will exert a stretching force thereon tending to bring the upper to its own size. This force will first stretch the upper and then cause the overlapped lasting margin to "creep" on the insole, the "leggy" cement permitting such creeping of the upper, to accommodate the larger last, while at the same time retaining an adhesive bond between the upper and the insole. However, inasmuch as the upper will not creep, at any point where it is secured to the insole, until a considerable force has been applied through the upper, when the last has been fully inserted, all portions of the upper will have been subjected to a uniform lasting stress, i. e., a stress sufficient to cause creeping of the upper on the insole. Thus, although the upper may not have been very carefully graded or its lasting margin accurately positioned on the insole, so long as the upper is appreciably smaller than the last, all portions of it will be substantially uniformly stretched and shaped to the last. After the last has been inserted and the upper stretched in the manner just described, the adhesive will set so as to bond the upper securely to the insole. This bond may, of course, be augmented when, in the subsequent step of applying an outsole, the outsole is attached by means of fastenings such, for example, as stitches which pass through the lasting margin of the upper and the insole.

It will be apparent, regardless of the manner in which the upper is adhesively secured to the insole or how the shoe is subsequently completed that, by the use of the machine of this invention, the operation of assembling the upper on, and securing it to, the insole, may be easily and speedily effected. Also, because of the action of the anvil and cooperating presser member, the lasting margin of the upper will be uniformly and firmly adhered to the insole. Furthermore, because of the function of the holdown in serving as a guide point, when assembling an upper on a rabbeted insole, or as a guide means, when assembling an upper on an insole which is not rabbeted or otherwise provided with means for locating the upper thereon, accurate positioning of the lasting margin on the insole is assured. Moreover, the lateral positioning of the insole, by the edge guide, and the holding of the insole on the table by the holdown, greatly facilitate the assembling operation and thus speed up production.

Having described the invention, what I claim

as new and desire to secure by Letters Patent of the United States is:

1. A machine for assembling an upper on a sole member having, in combination, means constructed and arranged to extend through the open end of an upper and adapted to support a sole member with the upper loosely assembled thereon, a member extending inside of the upper and located adjacent to the supporting means, and means cooperating with said last-mentioned member for applying pressure to the upper and sole member, progressively, to secure the upper to the sole member in assembled relation thereon.

2. A machine for assembling an upper on a sole member having, in combination, means constructed and arranged to extend through the open end of an upper and adapted to support a sole member with the upper loosely assembled thereon, a member extending inside of the upper and located adjacent to the supporting means, and means cooperating with said last-mentioned member for applying pressure to the upper and sole member, progressively, to secure the upper to the sole member in assembled relation thereon.

3. A machine for assembling an upper on a sole member having, in combination, means constructed and arranged to extend through the open end of an upper and adapted to support a sole member with the upper loosely assembled thereon, a member extending inside of the upper and located adjacent to the supporting means, and means cooperating with said last-mentioned member and including a rotary member for applying pressure to the upper and sole member, progressively, to secure the upper to the sole member in assembled relation thereon.

4. A machine for assembling an upper on a sole member having, in combination, means constructed and arranged to extend through the open end of an upper and adapted to support a sole member with the upper loosely assembled thereon, a member extending inside of the upper and located adjacent to the supporting means, and means cooperating with said last-mentioned member and including a rotary member for applying pressure to and for feeding the upper and sole member to secure the upper progressively to the sole member in assembled relation thereon.

5. A machine for assembling an upper on a sole member having, in combination, a table, supported on a flexible arm and adapted to extend through the open end of an upper, for supporting a sole member with the lasting margin of the upper loosely assembled in overlapping relation thereon, an anvil extending into the upper and supported on a flexible arm adjacent to said table, and a presser member cooperating with said anvil for applying pressure to the overlapped lasting margin of the upper and the sole member, progressively, to secure the upper to the sole member in assembled relation thereon.

6. A machine for assembling an upper on a sole member having, in combination, a table, supported on a flexible arm and adapted to extend through the open end of an upper for supporting a sole member with the lasting margin of the upper loosely assembled in overlapping relation thereon, an anvil extending into the upper and supported on a flexible arm adjacent to said table, and a rotary presser member cooperating with the anvil for applying pressure to the overlapped lasting margin of the upper and the sole member, progressively, to secure the upper to the sole member in assembled relation thereon.

7. A machine for assembling an upper on a sole member having, in combination, a table supported on a flexible arm and adapted to extend through the open end of an upper for supporting a sole member with the lasting margin of the upper loosely assembled in overlapping relation thereon, an anvil extending into the upper and supported on a flexible arm adjacent to said table, said anvil being supported for circular movement, a rotary presser member, and means for rotating said presser member and for imparting circular movement to the anvil, in time relation, so that the sole member and upper are fed along and the lasting margin of the upper progressively pressed against the sole member.

8. A machine for assembling an upper on a sole member having, in combination, means constructed and arranged to extend through the open end of an upper and adapted to support a sole member with the upper loosely assembled thereon, means for yieldingly holding the sole member on said supporting means, a member extending inside of the upper and located adjacent to the supporting means, and means associated with said last-mentioned member for applying pressure to the upper and sole member, progressively, to secure the upper to the sole member in assembled relation thereon.

9. A machine for assembling an upper on a sole member having, in combination, means constructed and arranged to extend through the open end of an upper and adapted to support a sole member with the upper loosely assembled thereon, means for yieldingly holding the sole member on said supporting means, a member extending inside of the upper and located adjacent to the supporting means, and a rotary member associated with said last-mentioned member for applying pressure to the upper and sole member, progressively, to secure the upper to the sole member in assembled relation thereon.

10. A machine for assembling an upper on a sole member having, in combination, means constructed and arranged to extend through the open end of an upper and adapted to support a sole member with the upper loosely assembled thereon, hold-down means for yieldingly holding the sole member on said supporting means, and means associated with said supporting means for applying pressure to the upper and sole member, progressively, to secure the upper to the sole member in assembled relation thereon, said hold-down means being also arranged to guide the edge of the upper as it is pressed against the sole member.

11. A machine for assembling an upper on a sole member having, in combination, means constructed and arranged to extend through the open end of an upper and adapted to support a sole member with the upper loosely assembled thereon, hold-down means for yieldingly holding the sole member on said supporting means, and means including a rotary member associated with said supporting means for applying pressure to the upper and sole member, progressively, to secure the upper to the sole member in assembled relation thereon, said hold-down means being also arranged to guide the edge of the upper as it is pressed against the sole member.

12. A machine for assembling an upper on a sole member having, in combination, means constructed and arranged to extend through the open end of an upper and adapted to support a sole member with the lasting margin of the upper loosely assembled in overlapping relation there-

on, hold-down means for yieldingly holding the sole member on the supporting means, an anvil extending into the upper and located adjacent to said supporting means, a presser member cooperating with the anvil for applying pressure to the overlapped lasting margin of the upper and sole member progressively to secure the upper to the sole member, said hold-down means being also arranged to guide the edge of said lasting margin as the upper is pressed against the sole member by the pressing member.

13. A machine for assembling an upper on a sole member having, in combination, means constructed and arranged to extend through the open end of an upper and adapted to support a sole member with the lasting margin of the upper loosely assembled in overlapping relation thereon, hold-down means for yieldingly holding the sole member on the supporting means, an anvil extending into the upper and located adjacent to said supporting means, and a rotary presser member cooperating with the anvil for applying pressure to the overlapped lasting margin of the upper and sole member, progressively, to secure the upper to the sole member, said hold-down means being also arranged to guide the edge of said lasting margin as the upper is pressed against the sole member by the pressing member.

14. A machine for assembling an upper on a sole member having, in combination, means constructed and arranged to extend through the open end of an inturned upper and to support a sole member with the inturned upper loosely assembled thereon, means for engaging the upper adjacent to the edge of the sole member for positioning the sole member laterally on said supporting means, a member extending inside of the upper and located adjacent to the supporting means, and a rotary member cooperating with said last-mentioned member for applying pressure to the upper and sole member on said supporting means, progressively, to secure the upper to the sole member in assembled relation thereon.

15. A machine for assembling an upper on a sole member having, in combination, means for supporting a sole member with an upper loosely assembled thereon, means for yieldingly holding the sole member on the supporting means, means for engaging the upper adjacent to the edge of the sole member for positioning the sole member laterally on the supporting means, a member ex-

tending inside of the upper and located adjacent to the supporting means, and means associated with said last-named member for applying pressure to the upper and sole member, progressively, to secure the upper to the sole member in assembled relation thereon.

16. A machine for assembling an upper on a sole member having, in combination, means constructed and arranged to extend through the open end of an upper and adapted to support a sole member with an upper loosely assembled thereon, means for yieldingly holding the sole member on the supporting means, means for engaging the upper adjacent to the edge of the sole member for positioning the sole member laterally on the supporting means, a member extending inside of the upper and located adjacent to the supporting means, and means associated with said last-named member for applying pressure to the upper and sole member, progressively, to secure the upper to the sole member in assembled relation thereon.

17. A machine for assembling an upper on a sole member having, in combination, means constructed and arranged to extend through the open end of an upper and adapted to support a sole member with an upper loosely assembled thereon, means for yieldingly holding the sole member on the supporting means, means for engaging the upper adjacent to the edge of the sole member for positioning the sole member laterally on the supporting means, a member extending inside of the upper and located adjacent to the supporting means, and a rotary member associated with said last-named member for applying pressure to the upper and sole member, progressively, to secure the upper to the sole member in assembled relation thereon.

LLOYD G. MILLER.
